CLAIM

The ornamental design for a ventilating hood for an electroplating tank, substantially as shown and described.

DESCRIPTION

FIG. 1 is a perspective view showing a ventilating hood for an electroplating tank showing our new design; FIG. 2 is a cross-sectional view thereof taken along the line 2—2 of FIG. 1;

FIG. 3 is a front elevational view thereof;

FIG. 4 is a rear elevational view thereof; and

FIG. 5 is a reduced scale bottom plan view thereof.

FIGS. 3, 4 and 5 have a center portion broken away for convenience of illustration only.
